UNITED STATES PATENT OFFICE.

CONRAD KLAIBER AND ALFRED CURRIER, OF GRAND RAPIDS, MICHIGAN.

COMBINED CIGAR CLIPPER AND PERFORATOR.

SPECIFICATION forming part of Letters Patent No. 289,351, dated November 27, 1883.

Application filed August 17, 1883. (No model.)

To all whom it may concern:

Be it known that we, CONRAD KLAIBER and ALFRED CURRIER, citizens of the United States, residing at Grand Rapids, in the county 5 of Kent and State of Michigan, have invented a new and useful Cigar Clipper and Perforator, of which the following is a specification.

Our invention relates to improvements in a cigar-clipper, in which a knife shaped at the 10 end on an angle to produce a shear cut, and also provided with spurs or perforators, (both operated by the same movement,) are employed.

In the accompanying drawings, Figure 1 is 15 a plan view of the top of the case, showing the openings to receive cigars. Fig. 2 is a view of the top of the inner case with the cover removed, showing the knives and spurs ready to operate. Fig. 3 is a vertical side section; 20 Fig. 4, an end section.

Similar letters of reference refer to corresponding parts throughout these several figures.

O O in Fig. 1 represent the openings to receive the cigars for clipping.

25 P represents an opening to receive cigars to be perforated.

E E show plates to which the knives and spurs are soldered.

F represents a bar in the inner case on which 30 the plates rest. The line R shows the width of a steel knife, which is fastened to a plate, E. N are spurs attached to the plates E. The plates may be made of cast-iron, and steel knives and spurs soldered on, or they may be 35 punched out of sheet-steel.

L L represent rods or screws which pass through the outer case, C, and form bearings for arms G G.

K K represent ears on plates E E, to which 40 the arms G G are attached by means of pins M.

I I represent screws by which the cover A is fastened to the inner case, B, by means of lugs S S.

D represents a wooden base.

T represents a bar that slips over lugs u, 45 (shown in Figs. 3 and 4,) holding the base in place. This bar T is fastened to the base by means of screws or staples V V, as shown in Fig. 3.

H H are coiled springs hooking over screws 50 I I, and into holes J J of arms G G. When the inner case is pressed down, it is drawn back quickly by means of these springs H H.

Dotted lines W in Figs. 3 and 4 show the form of the inner case. When the inner case is 55 pressed down, it throws the knives past openings O O, thereby making a clear shear cut, and with the same movement the spurs N N are thrown forward, passing each other and under the opening P, driving them through the 60 end of a cigar placed therein.

What we claim as our invention, and desire to secure by Letters Patent, is—

1. Inner case, B, having openings O O and P in the top A, in combination with knives E 65 E, having spurs N N, attached thereto, as described, cross-bar F, box C, and pivoted arms G G, arranged substantially as described, and for the purposes set forth.

2. Cases B and C, in combination with knives 70 E E, having spurs N N, cross-bar F, arms G G, rods L L, and springs H H, arranged substantially as described, and for the purposes set forth.

3. Cases B and C, having bar F, knives E 75 E, having spurs N N, arms G G, rods L L, and springs H H, in combination with removable base D, arranged substantially as described.

CONRAD KLAIBER.
ALFRED CURRIER.
